HOWARD I. MORRIS, OF LAKEWOOD, OHIO, ASSIGNOR TO THE YODER-MORRIS COMPANY, OF CLEVELAND, OHIO, A CORPORATION OF OHIO

HINGING MEANS

Application filed May 29, 1929. Serial No. 366,931.

The present invention relates to hinges or hinging means and has for one of its objects to provide a novel hinge construction embodying a roller bearing and an adjustment therefor.

Another object of the invention is to provide a pair of hinges wherein parts thereof may be relatively adjusted to distribute the weight of a door or the like uniformly on both 10 hinges.

A further object is to provide a novel arrangement of hinging means, having tapered roller bearings, which are oppositely disposed and capable of independent adjustment to insure accuracy and even distribution of weight on the parts of each hinge means and to provide a practical and efficient structure admitting economical and quick assembly of the bearings and other parts and 20 wherein the bearings are protected and easily adjusted.

Another object of the invention is to provide a hinge having tapered roller bearings so disposed that both the radial and thrust 25 load is borne directly by the rollers of said bearings.

Another object of the invention is to provide a hinge having tapered roller bearings between its relatively movable elements so 30 mounted that frictional contact between the two elements of the hinge, except that incident to the rolling contact of tapered rollers, is eliminated, so that the friction is reduced to a minimum.

35 The above and various other objects and advantages of this invention will in part be described in, and in part be understood from, the following detailed description of the present preferred embodiments, the same being illustrated in the accompanying drawings, wherein:

Fig. 1 is a fragmentary front elevation, partly broken away, of a building provided with a swinging door equipped with hinges 40 constructed according to the present invention.

Fig. 2 is a detail enlarged fragmentary section taken substantially on the line 2—2 of Fig. 1 and showing one of the hinges connecting a door section to the building.

Fig. 3 is a detail enlarged fragmentary vertical section taken through the hinge substantially on the line 3—3 of Fig. 2, and

Fig. 4 is a top plan view of a slightly modified form of hinge, the same being attached 55 to adjacent door sections, portions of the latter being shown.

Fig. 5 is an elevation of the parts shown in Fig. 4.

Referring now to the drawings, and first 60 to the form of hinge shown in Figures 1, 2 and 3, the hinge is disclosed as mounted upon a building 10, a wall or other suitable enclosure the opening through which is adapted to be closed by a door or doors 11.

As shown in Figures 2 and 3, one member 65 or part of the hinge comprises a bracket plate 13 adapted to be secured vertically against the outer side of the wall 10 by bolts 14 or the like. The bracket plate 13 is provided with upper and lower lugs 15 in vertically spaced apart relation, and these lugs project outwardly from the plate and are provided with threaded axially aligned apertures 16 adjustably receiving therethru threaded studs 17 70 which are preferably kerfed in their outer ends for the reception of the bit of a screw driver or the like for turning the studs 17 and adjusting their inner ends toward and from each other. Set screws 18 may also be 75 provided in the lugs 15, threaded through the wall of the latter and adapted to bind against the studs 17 after the same have been adjusted for locking the latter in adjusted position.

The other part or member of the hinge comprises a strap 19 adapted to be secured to the adjacent portion of the door 11, as shown to 80 advantage in Figure 2. The strap 19 extends over the outer side of the wall 10 to the bracket plate 13 and is provided thereat with 85 a knuckle 20.

The knuckle 20 is of any suitable configuration and fits loosely between the lugs 15 and is adapted to be supported therebetween and to be shifted vertically between the lugs to 90 effect a relative adjustment between the bracket plate 13 and the strap 19.

At each end, the knuckle 20 is enlarged and hollowed out to provide bearing cups 21, and the studs 17 are provided with projections or 100

reduced inner ends adapted to project into the cups 21 to support the bearing members. The bearing members comprise an outer race 22 which is seated in the cup 21 and in which travel the taper rollers 23. The adjacent stud 17 carries upon its reduced end an inner race 24 which, by adjustment of the lug 17, bears against the rollers 23 and thus supports the adjacent end of the knuckle 20.

10 Suitable means for lubricating the bearings is provided, the same comprising lubricating chambers 25, which are formed in the opposite end portions of the knuckle 20 and open into the cup 21. Grease cups 26 are preferably threaded through one side of the knuckle 20 and lead into the chambers 25 through suitable ports or the like so as to supply a suitable grease or oil to the chambers 25 and to admit of the packing of the lubricant 20 therein.

It will be noted that the bearing members are of tapering construction and that they taper inwardly towards each other so as to serve as both radial and thrust bearings for 25 supporting the knuckle 20 and the parts connected thereto against endwise displacement, and to take up the weight of the door or the like through the knuckle 20, the bearing members, the stud 17 and the lug 15 to the bracket 30 plate 13. It will also be readily appreciated that the knuckle 20 may be shifted vertically between the lugs 15 by the relative adjustments of the studs 17 so that when the hinges are in pairs the weight of the door or other 35 device suspended from the hinge, may be equalized between the upper and lower hinges so that the entire weight and strain will not be imposed upon but one of the hinges. Further, by adjusting the hinges it is readily seen 40 that the door may be correctly aligned with a second door, or a door section, or may be adjusted to provide for the necessary clearance at the upper or lower edges of the door. While the hinges are capable of fine adjustment, at the same time they may be constructed 45 relatively large so as to withstand considerable weight and abuse incident to the mounting of the knuckle 20 at opposite ends between the tapered bearing members. In the 50 modification shown in Figure 4 the structure of the hinge is the same as that shown in Figure 3, with the exception that the attaching bracket or straps 27 and 28 are of different shape to adapt the hinge to the door sections 55 11 and 12. In the modification shown in Figures 4 and 5 one of the straps, such as the strap 27, carries the lugs 15 while the strap 28 is provided with the knuckles 29 and the 60 other parts as shown in Figure 3 to complete the hinge structure.

It is of course understood that various changes and modifications may be made in the details of construction and design of the 65 above specifically described embodiments,

such changes and modifications being restricted only by scope of the following claim.

What is claimed is:

A hinge, comprising related members, one member having spaced apart knuckles formed with aligned registering threaded openings therethrough and the other member having a knuckle fitting between said spaced knuckles and having oppositely disposed cupped ends, an outwardly flaring race seated in each cupped end of the last mentioned knuckle, roller bearings seated on each of said races, a stud threaded through each of the first mentioned knuckles and projecting into the adjacent cupped end of the last mentioned knuckle, and an outwardly tapering race on each stud engaging said roller bearing to support the last mentioned knuckle through the bearings on the first mentioned knuckles, said studs being adapted for independent adjustment in the first mentioned knuckles to shift the last mentioned knuckle endwise therebetween and to distribute the supporting pressure and radial thrust on both 90 bearings.

In testimony whereof, I have hereunto affixed my signature.

HOWARD I. MORRIS.
